No. 764,352.

PATENTED JULY 5, 1904.

W. F. COOPER, JR. & H. E. SHARPS.

REVERSING AND SPEED REGULATING DEVICE FOR MUSICAL INSTRUMENT
CONTROLLING SHEETS.

APPLICATION FILED JAN. 9, 1904.

NO MODEL.

UNITED STATES PATENT OFFICE.

WILLIAM F. COOPER, JR., AND HERBERT E. SHARPS, OF CHICAGO,
ILLINOIS, ASSIGNORS TO THE CABLE COMPANY, A CORPORA-
TION OF ILLINOIS.

REVERSING AND SPEED-REGULATING DEVICE FOR MUSICAL-INSTRUMENT CONTROLLING-SHEETS.

SPECIFICATION forming part of Letters Patent No. 764,352, dated July 5, 1904.

Application filed January 9, 1904. Serial No. 188,320. (No model.)

To all whom it may concern:

Be it known that we, WILLIAM F. COOPER, Jr., and HERBERT E. SHARPS, both citizens of the United States, and both residing at Chicago, county of Cook, and State of Illinois, have invented new and useful Improvements in Reversing and Speed-Regulating Devices for Musical-Instrument Controlling-Sheets, of which the following is a specification, reference being had to the accompanying drawings, forming a part thereof.

This invention relates to motors for operating the controlling-sheet of automatic musical instruments and to means for regulating the speed and reversing the action.

It consists in the features of construction set out in the claims.

In the drawings, Figure 1 is a plan view of a motor having the regulating and reversing devices constituting our invention, same being shown in connection with the take-up and rewinding rolls of the player, the parts being shown in position of rest. Fig. 2 is a plan view of the same parts, the motor-train being shown only in outline, the adjusting parts being shown in full line in position for operating the take-up or winding roll at slow speed and in dotted lines at two positions, the first that for operating the take-up roll at high speed and the second position for disconnecting the take-up roll without interrupting or modifying the speed of the motor.

The motor shown in the drawings is constructed according to our Patent No. 697,754, dated April 15, 1902, and need not be here described beyond calling attention to the fact that it has a centrifugal governor 1, through which the speed of the motor is regulated by the friction-brake 2 bearing upon the disk 3 of the governor and adjustable by the mechanism hereinafter described to vary the point at which it arrests the longitudinal movement of the disk due to the centrifugal movement of the governor, and thereby limits the speed, employing a familiar expedient. The mechanism comprises the shaft 4, terminating in the chuck 4^a, for engaging and rotating the rewinding-roll, (not shown;) a sleeve-shaft 5,

having a pinion 6 engaging a gear 7 on the take-up or winding roll B; a shaft 8, telescoping at one end and obtaining bearing thereby within the sleeve-shaft 5 and journaled at the other end in a bracket 9; a sprocket-wheel 10, fast on the shaft 4; a sprocket-wheel 11, loose on the shaft 8 and having its hub provided with a groove 11^a, which is engaged by a fixed finger 12 on the bracket 9 for holding the sprocket-wheel 11 in position against lateral displacement.

On the end of the sleeve-shaft 5 opposite that which carries the pinion 6 said shaft has a clutch element 13, and the shaft 8 is adapted to be thrust back and forth through its bearing in the bracket 9 and in the sleeve-shaft 5, and for the purpose of such movement it has a clutch-collar 14 fast on it, provided at one end with a projection 14^a for engaging the corresponding projection 11^b on the end facing the clutch-collar of the hub of the sprocket-wheel 11 and at the other end a corresponding projection 14^b for engaging the clutch-collar 13 on the sleeve-shaft 5, the lever 15, pivoted on the base-board 16, on which the entire structure is mounted, having a finger 15^a engaging a peripheral slot in the clutch-collar 14 for moving the shaft longitudinally back and forth as the lever is rocked, and thereby carrying the clutch into engagement either with the sleeve-shaft 5 for rotating the pinion 6, gear 7, and take-up roll B or into engagement with the sprocket-wheel 11 for rotating by means of the chain 10^a the sprocket-wheel 10, shaft 4, and the rewinding-roll.

At the end of the shaft 8 outside the bracket 9 said shaft carries rigidly the sprocket-wheel 17, connected by a chain 18 with the sprocket-wheel 19 on the end of the final shaft of the train, which is mounted in the motor-frame C for deriving from the motor the power for rotating the rolls according to the adjustment of the mechanism provided for that purpose.

On the motor-frame C there is fulcrumed the lever 20, which is forked to provide it with two fingers at opposite sides of the governor-shaft, on each of which it carries a brake-pad 21 for contact with the governor-

disk 3. The rear end of the lever 20 is connected by an extensible link 22 22^a with the lever 23, which is fulcrumed on the base-board 16, said connection being made directly to an 5 adjustable plate 24 on said lever 23, so that the distance of the pivotal connection of the link 22 22^a from the fulcrum of the lever 23 may be varied to vary the maximum speed of the governor. For such adjustment of the 10 plate 24 it has two slots 24^a 24^b, through which screws 24^b 24^b pass to secure it to the lever 23. The lever 15 has an arm 15^b projecting in general toward the fulcrum of the lever 23, and said lever 23 has a spring-finger 23^a, which 15 extends in position to engage the arm 15^b when the lever 23 is swung about its pivot to the left—that is, in direction for causing the link 22 22^a, operating on the lever 20, to carry the friction-pads of said lever away from the 20 governor-disk to permit acceleration of the latter. The collision or engagement of the spring-finger 23^a with the lever-arm 15^b in the movement described operates the lever 15 in direction for disengaging the clutch 14 from the 25 sprocket-wheel 11 and engaging it with the clutch-collar 13 on the end of the sleeve-shaft 5 to rotate the pinion 6, gear 7, and winding-roll B. The spring-finger 23^a of the lever 23 runs off the end of the arm 15^b of the lever 15 after 30 operating said lever 15 sufficiently to effect the engagement of the clutch 14 with the clutch 13. On the end of the sleeve-shaft 5 and during a further range of movement of the lever 23 in the same direction as that for causing said 35 clutch engagement it will be noticed that the friction-brake 2 is being carried in direction for permitting acceleration of the motor. For operating the lever 23 we provide a lever 25, fulcrumed on the under side of the base-board 16, having a finger 25^a projecting up from a slot 16^a in the base-board and connected by a link 26 with the lever 23, so that the operator by swinging the finger 25^a back and forth in the slot 16^a operates the lever in 40 either direction to any desired extent within the range of construction. The link 26 has an offset or arm 27, which is adjustable longitudinally on the link and projects therefrom in position to encounter an abutment 15^c 45 on the lever 15 at a position of said lever corresponding to the maximum speed of the motor, said maximum being thus determined by the adjustment of said offset or arm 27 on the link. The engagement of the arm 27 with the lever 15 being at the opposite side of the fulcrum of said lever from that at which the finger 23^a of the lever 23 engages the lever 15, the movement of the latter lever caused by the encounter therewith subsequent to the 50 movement of the arm 27 is in the reverse direction from that which said lever 15 in the earlier part of the movement of the stop-finger 25^a derives from the lever encounter of the spring-finger 23^a, and in such reverse movement the finger 15^a, engaged with the clutch 60

14, moves said clutch out of engagement with the clutch 13 and into engagement with the gear 11, causing the winding-roll to come to rest and the rewinding-roll to be actuated. The movement of the lever 23 for such reversal of the clutch connections and shifting the motive power from the winding to the rewinding roll carries the governor-brake 2 still farther in the direction for accelerating the speed of the motor and permits the latter to 70 run at the limit of its speed, or practically without control by the brake while operating the rewinding-roll, thus giving said roll the highest speed within the power of the motor for rewinding the controlling-sheet as quickly 75 as possible. The finger 23^a is made elastic for the purpose of permitting it to yield as the lever 15 is operated by the arm 27 of the link 26 for swinging the lever 15 in the direction for disengaging the winding-roll train 80 and engaging the rewinding-roll train. When in resetting the lever 25 to rest position by means of the stop-finger 25^a the end of the spring-finger 23^a will run off the end of the arm 15^b of the lever 15 and snap back 90 to its original position behind said arm ready for engagement of its end therewith, as before. See, in Fig. 2, dotted-line position of said finger just ready to run off the end of the arm 15 and full-line position after it has 95 snapped back to original rest position. In order to render it possible to arrest the action of the winding-roll without stopping the motor or the main train operated by it and reengage the winding-roll of the train at 100 will, so that the rotation of the latter may be resumed at substantially the speed which it had before disconnection, (such action being desirable in playing to preserve the "tempo" notwithstanding such an interruption,) the 105 distance between the facing ends of the two elements which are engaged by the clutch 14—to wit, the hub of the sprocket-wheel 11 and the clutch 13 on the end of the sleeve-shaft 5—is such as to allow said clutch 14 to 110 stand intermediate the two without engagement with either, and the lever 15 for operating said clutch is connected by a link 28 with a stop-lever 29, fulcrumed on the foundation-board 16 and having a stop-finger 29^a for operating it protruding through the slot of the platform-board in the same manner as the stop-finger 25^a, and at the margin of said slot there is provided an index-mark 30, indicating the position at which said stop-finger 29^a 115 stands when the clutch 14 is intermediate its two engagements, so that the motor is not driving either the winding-roll or the rewinding-roll. By moving said stop-finger 29^a to this position the operator will cause either the 120 winding-roll or the rewinding-roll, whichever may be in operation at the time, to come to rest while the motor continues its action. This operation, if performed while the winding-roll is running, merely takes the abut- 125 130

ment 15° of the lever 15 away from the arm 27 on the link 26, and although if performed when the rewinding-roll is in action the direction of movement of the abutment 15° is such upon its encounter with the arm 27 as to thrust the link 26 and swing the lever 23 in direction for retarding the motor such retardment will only reduce its speed to the maximum winding speed, and in the instances 10 in which it is desired to interrupt the rewinding in this manner the mere retardment of the motor to this extent is not objectionable.

The link 22 22^a is rendered extensible by the slotted connection of the two elements 22 22^a, by means of the clamping-bolt 22^b, and such extensibility facilitates the correct adjustment of the parts in mounting them upon the base-board 16, in respect to which absolute uniformity and consequent accuracy of adjustment for the governor would be difficult to obtain, and it is rendered unnecessary by said adjustability of the link and also further by the adjustability of the plate 24 on the lever 23.

We claim—

- 25 1. In combination with the take-up and rewinding rolls, a motor for driving them; a shaft operated continuously by the motor; a train for operating the rewinding-roll commencing with a wheel loose on said shaft; a train for operating the take-up roll comprising a shaft with which said continuously-driven shaft is telescoped at one end; a clutch element on said take-up-roll train-shaft; a clutch fast on the continuously-driven shaft, adapted at one side for engagement with said clutch element and at the other side for engagement with the loose wheel, and means for shifting the shaft to engage the clutch at either side at will.
- 30 2. In combination with the take-up roll and the rewinding-roll, a motor for driving them; a shaft driven continuously by the motor, said shaft being movable longitudinally in its bearings, and connections by which when moved in one direction the shaft operates the take-up roll, and when moved in the other direction operates the rewinding-roll; a lever having a fixed fulcrum; a governor friction-brake and connections from said lever to said 35 brake; a lever which engages the shaft for shifting it, and arms carried by the first-mentioned lever and its operating connections in position to encounter the second lever successively at opposite sides of the fulcrum of the latter in the continuous movement of said first lever and connections in the direction for withdrawing the governor-brake, whereby such continuous movement operates the shaft first in one direction and then in the other.
- 40 3. In combination with the take-up and rewinding rolls, the motor which operates them; an element and connections therefrom to the two rolls for operating one of them at one position and the other at another position of said element; a lever for moving said element

from one position to the other, the motor having a governor; a friction-brake for said governor, and a lever and connections therefrom for operating the brake; means for operating the second-mentioned lever at will, and connections from said second lever for engaging the first successively at opposite sides of its fulcrum in the movement of the second lever continuously in the direction for accelerating the motor.

4. In combination with the take-up and rewinding rolls, the motor for operating them; an element for changing the driving connections from one roll to the other by movement of said element in opposite directions; a lever for so moving it; a second lever for communicating such movement; connections from the second lever for regulating the speed of the motor, said levers being provided with means for engaging each other at two points, 85 said points on one of said levers being at opposite sides of the fulcrum of said lever.

5. In combination with the take-up and rewinding rolls, a motor for driving them; a shaft operated continuously by the motor; a 90 train for operating the rewinding-roll commencing with and comprising a wheel loose on said shaft; a gear-train for operating the take-up roll commencing with and comprising a clutch element loose on said shaft; a 95 clutch fast on the shaft adapted at one side for engagement with said clutch element and at the other side for engagement with the loose wheel; a lever for shifting the shaft to engage the clutch at either side at will; the motor having a governor and connections for operating it; the shaft-shifting lever having two arms on opposite sides of its fulcrum and the governor-operating connections comprising arms encountering the said two lever-arms for movement of said lever in opposite directions during the movement of the governor-operating connections continuously in the direction for accelerating the governor.

6. In combination with the take-up and rewinding rolls, a motor for operating them; an element for changing the driving connections from one roll to the other by movement of said element in opposite directions; a lever for so moving it and stop connections for operating said lever at will; means for regulating the speed of the motor comprising connections which encounter said lever in the movement of said connections for acceleration of the governor to rock the lever in direction for disengagement of the clutch from the take-up roll.

7. In combination with the take-up and rewinding rolls, a motor for operating them; a continuously-driven shaft operated by the motor adapted to be moved endwise in its bearings, the clutch, 14, fast on said shaft; a train for operating the rewinding-roll and a train for operating the take-up roll having clutch elements loose on said shaft at opposite sides 130

- of the fast clutch, the lever, 15, having an arm engaging the clutch for shifting the shaft; stop connections for operating the lever at will; a brake for regulating the governor; 5 connections for operating the brake comprising a lever, 20; stop connections for operating said lever; two projections operated with said brake-operating lever, and connections for engaging the lever, 15, at opposite sides 10 of its fulcrum during the movement of said connections in direction for accelerating the motor.
8. In combination with the take-up and re-winding rolls, the motor and connecting trains 15 for operating them; a brake for regulating the governor; a lever for operating the brake; a second lever having stop connections and a link connecting it with the first lever, said link being extensible for adjusting the brake.
- 20 9. In combination with the take-up and re-winding rolls, the motor and trains for operating them; a brake for regulating the motor; a lever which operates said brake; a foundation-board upon which the motor and trains 25 are mounted; a second lever mounted on the

foundation-board; a plate adjustable on said lever; link connections from the plate to the brake-operating lever, said plate being adjustable on the second lever to vary the relation of the brake-lever-connection pivot to the 30 lever-fulcrum.

10. In combination with the take-up and re-winding rolls, a motor and trains for operating them; a brake for regulating the governor; a lever for operating the brake; a second lever having a fixed fulcrum and an extensible link connecting with the first lever a plate mounted adjustably on the second lever having the said link pivoted to it for making said connection between the levers. 35

In testimony whereof we have hereunto set our hands, in the presence of two witnesses, at Chicago, Illinois, this 7th day of December, 1903.
